UNITED STATES PATENT OFFICE.

JOSEPH DORWEILER, OF WEST BEND, IOWA.

CONCRETE-MIXER.

No. 821,790.

Specification of Letters Patent.

Patented May 29, 1906.

Application filed June 20, 1905. Serial No. 266,135.

To all whom it may concern:

Be it known that I, JOSEPH DORWEILER, a citizen of the United States, residing at West Bend, in the county of Palo Alto and State of Iowa, have invented a new and useful Concrete-Mixer, of which the following is a specification.

This invention relates to concrete-mixers.

The object of the invention is to provide an apparatus which will in a rapid and continuous manner mix sand and concrete in predetermined quantities and hydrate and discharge them as a thoroughly incorporated and finished product.

With the above and other objects in view, as will appear as the nature of the invention is better understood, the same consists in the novel construction and combination of parts of a concrete-mixer, as will be hereinafter fully described and claimed.

In the accompanying drawings, forming a part of this specification, and in which like characters of reference indicate corresponding parts, Figure 1 is a view in side elevation, partly in section, of a machine constructed in accordance with the present invention. Fig. 2 is a view in end elevation, partly in section. Fig. 3 is a sectional detail view through the mixing-hopper, taken on the line 3 3, Fig. 1. Fig. 4 is a detail view in plan of a rotary mixer used in connection with the apparatus. Fig. 5 is a sectional detail view taken on the line 5 5, Fig. 1, and looking in the direction of the arrow thereon.

The base of the machine comprises a pair of ordinary sill-beams 1, that support two pairs of vertical beams 2, a pair of vertical beams 4, that are connected by a cross-beam 5, and a pair of longitudinal beams 4^a, that connect the beams 2 and 4 and are disposed on the inner sides thereof. Supported by the longitudinal beams 4^a is a mixing-trough 3, the upper edges of which are outturned to form flanges 3^a, that are bolted or otherwise secured to the beams 4^a, and is thereby firmly supported in operative position. Supported upon the beams 4^a, as by two pairs of channel-beams 6, is a casing 7, that is divided by a partition 8 into two hoppers 9 and 10, the former of which is to receive sand and the latter cement, the escape of material from the discharge-mouths 11 of the hoppers being controlled by slides or cut-offs 12. (Clearly shown in Figs. 1 and 3.)

Extending through the two compartments and journaled in suitable bearings therein is

a shaft 13, carrying two sets of beater-arms 14, one set being arranged in the compartment 9 and the other set in the compartment 10, the lower ends of the beaters being disposed to travel close to the mouths of the hoppers, as shown in Figs. 1 and 2. The shaft 13 carries on one end a bevel-gear 15, which is engaged by a similar gear 16, carried by one end of a counter-shaft 17, journaled in suitable bearings 18 in the conveyer-casing 22, the other end of the counter-shaft having secured to it a sprocket-wheel 19, which is driven by a sprocket-chain 29, as shown in Fig. 2.

The conveyer-casing 22, as shown in Fig. 2, is disposed on an incline and has combined with its lower end a feed-hopper 23, in which is arranged a screen 24, that is adapted to separate out from the sand trash and stones in the usual manner. There is also an agitator 20, arranged in the feed-hopper, the shaft of which carries a sprocket-wheel 21, which is engaged by a sprocket-chain 21^a, driven from a sprocket-wheel 21^b, carried by the shaft 28. The elevator 25 is of the common bucket type and passes around sheaves or pulleys 26 and 27, disposed, respectively, at the lower and upper ends of the conveyer-casing, the pulley 26 being mounted upon a shaft 28, journaled in suitable bearings on the base 1, and the pulley 27 being mounted upon the shaft 21^x.

The shaft 27 is driven by a sprocket-chain 29, which engages, respectively, a sprocket-wheel 30, carried by the shaft 21, and two sprocket-wheels 31 and 32, carried by shafts 33 and 34, journaled beneath the hopper 7. Arranged beneath each of the hoppers 11 is a trough or box 35, within each of which is mounted a screw conveyer 36, carried by the shaft 33 and a similar shaft 37, which are journaled in suitable bearings in the ends of the troughs. The shafts 33 and 37 each project at one end beyond the trough, the shaft 33, as before stated, having a sprocket-wheel 31 combined with it and the shaft 37 having a sprocket-wheel 38 combined with it. The shaft 33 carries a third sprocket-wheel 39, and the two sprocket-wheels 38 and 39 are engaged by a sprocket-chain 40, which operates to drive the two screw conveyers in unison.

Arranged below the troughs 35 is a hopper 41, into which the two troughs discharge through openings 42 in their bottoms, and the hopper 41 projects into a circular recep-

tacle 43, the lower end 44 of which is funnel-shaped and discharges into the mixing-trough 3, as clearly shown in Fig. 2.

Mounted in a bearing 45, secured to the upper side of the mixing-trough, and in a bracket 46, secured to the under side of the hopper 7, is a vertical shaft 47, upon which is mounted a rotary mixing-disk 48, that carries a plurality of arms or beaters 49, which are disposed tangential to the shaft 47, as clearly shown in Fig. 4. The object of this disk is to catch the sand and cement as it passes from the respective troughs and by centrifugal force throw it violently against the walls of the receptacle 43, thereby to cause thorough mixing of the ingredients and also the breaking up of any lumps that might be present and which would militate against the production of a perfect concrete. The shaft 47 carries on its upper end a bevel-gear 50, which meshes with a bevel-gear 51, mounted on the shaft 34, the latter having secured to it a sprocket-wheel 32, which is driven by the sprocket-chain 29.

The mixing-trough 3 will, as shown in Fig. 5, be approximately semicircular in cross-section and is arranged on a slight incline, the discharge end of the trough having combined with it a spout 52. Mounted in a bearing 30 carried by a bracket 53^a, supported by the trough and by a bearing formed in the head 53^b of the trough, is a shaft 53, upon which is secured a plurality of obliquely-disposed arms 54, that operate to feed the concrete through the trough and also to break it up and mix it, so that by the time it reaches the spout 52 the ingredients will have been thoroughly commingled. The shaft 53 is driven from a pulley 55, that connects with a suitable source 40 of power. (Not necessary to be shown.) The shaft 53 carries a sprocket-wheel 56, around which passes a sprocket-chain 57, and around a sprocket-wheel 58 on the shaft 33, and from this point all of the operative parts of the machine are actuated.

Arranged over the trough 3, at any preferred point of its length, preferably about midway thereof, is a tank 59 to contain water, connecting with which is a valved pipe 60, carrying a longitudinally-disposed sprinkling-pipe 61, which supplies water in requisite quantity to the trough, thereby to effect hydration of the cement ingredients.

In the use of the apparatus sand is supplied to the hopper 23 and is carried upward by the conveyer 25 and discharged into the

hopper 9, while the cement is supplied from any suitable source to the hopper 10. The ingredients are then subjected to the beating action of the arms 14 and escape through the bottom of the hoppers 11 into the trough 35, whence they are discharged by the screw conveyers 36 to the hopper 41, thence to the rotary mixer 48, and thence to the trough, whence they are moved along by the arms 54 65 and finally discharged.

The operation is rapid and continuous and the output of the machine is only limited by the speed at which its operative parts are driven and the amount of material supplied. 70 When it is desired to stop the operation of the machine, the slide or valves 12 are closed or by regulating these latter elements the discharge of the materials can be controlled.

Having thus described the invention, what 75 is claimed is—

1. In a concrete-mixer, the combination of an endless conveyer, a feed-hopper forming a continuation of the lower end thereof and provided with a screen, a two-part discharge-hopper arranged at the upper end of the conveyer and into one of which it discharges, rotary beaters arranged within the discharge-hoppers, means for removing the materials from the discharge-hoppers, means for breaking up the mixed materials as they escape from the removing means, and a mixing-trough, including agitating and hydrating mechanisms, into which the materials discharge. 90

2. In a concrete-mixer, the combination of an endless conveyer, a feed-hopper forming a continuation of the lower end thereof and provided with a screen, agitating mechanism arranged within the hopper, a two-part discharge-hopper arranged at the upper end of the conveyer and into one of which it discharges, rotary beaters arranged within the discharge-hoppers, means for removing materials from the latter hoppers, means for breaking up the mixed materials as they escape from the removing means, and a mixing-trough including agitating and hydrating mechanisms into which the materials discharge. 95 100

In testimony that I claim the foregoing as 105 my own I have hereto affixed my signature in the presence of two witnesses.

JOSEPH DORWEILER.
